FEELER-MOTION FOR LOOMS.

1,308,193.

Specification of Letters Patent.

Patented July 1, 1919.

Application filed September 19, 1917. Serial No. 192,188.

To all whom it may concern:

Be it known that I, ALONZO E. RHOADES, a citizen of the United States, residing at Hopedale, county of Worcester, and State of Massachusetts, have invented an Improvement in Feeler-Motions for Looms, of which the following description, in connection with the accompanying drawings, is a specification, like characters on the drawings representing like parts.

The invention to be hereinafter described relates to feeler motions for looms, and more particularly to that type of feeler motions wherein upon substantial exhaustion, but prior to complete exhaustion, the feeler is given a side swipe movement in a direction substantially longitudinal of the shuttle.

In the practical use of feeler motions, many disturbing factors are experienced which tend to destroy the accuracy and reliability of the mechanism. Should the disturbing factors cause the filling to be fully exhausted before the feeler motion initiates filling replenishment, a defect in the cloth is liable to occur, while on the other hand, should the feeler mechanism act to effect replenishment prematurely, or while a working supply of filling yet remains in the shuttle, excessive waste is produced.

In feelers of the side swipe type, the side swipe or detecting movement of the feeler is inaugurated whenever the feeler fails to be held by a sufficient supply of filling in the shuttle. Such movement may be effected when only a few turns of filling yet remain in the shuttle, or when the feeler feels the more dense material of the bobbin within the shuttle. Likewise, should the shuttle fail to be properly boxed, the feeler will engage the smooth surface wall of the improperly boxed shuttle, and its side swipe or detecting movement will be effected. Under these conditions then, replenishment is not desired.

An important feature of the present invention, therefore, consists of a side swipe feeler normally under the influence of means tending to impart its side swipe movement, and a lock normally acting to prevent such feeler movement until the filling has reached a predetermined degree of exhaustion, and then freeing the feeler that it may respond to the means tending to move it laterally or longitudinally of the shuttle when the filling becomes substantially exhausted.

When the shuttle fails to be properly boxed, it is expedient that the feeler shall not perform its side swipe movement to initiate filling replenishment, and the present invention has for another important feature thereof, a lock for the feeler mounted independently of the feeler, and movable relatively thereto to maintain its locking relation with the feeler, should the latter on a detecting beat find the shuttle improperly boxed.

In the present invention the feeler is given its side swipe or detecting movement by spring actuated means along which the feeler travels as it is moved frontwardly on a detecting beat, and in order that the feeler may be relieved of the action of said means when the feeler is to resume its feeling or rearward position, provision is made to withdraw said means from operative relation with the feeler as the lay goes back.

Another important feature of the invention consists in a flexible member movable lengthwise by the side swipe movement of the feeler to initiate filling replenishment when the filling is substantially exhausted.

These and other features of the present invention will hereinafter be described in connection with one form or embodiment thereof as illustrated in the accompanying drawings, wherein:

Figure 1 is a perspective view of a portion of the feeler side of a loom provided with the present invention, only sufficient parts being shown to make clear the relation and operation of parts pertaining to the invention;

Fig. 2 is a perspective view of parts of the feeler motion showing certain details in separate relation;

Fig. 3 is a perspective detail on an enlarged scale showing the filling engaging end of the feeler and the end of the lock for holding the feeler from side swipe movement;

Fig. 4 is a plan view on an enlarged scale showing the action of parts of the feeler motion when a working supply of filling is present in the shuttle on a detecting beat;

Fig. 5 is a view similar to that of Fig. 4 showing action of the feeler motion when the filling is substantially exhausted;

Fig. 6 is a front view partly in perspective and partly broken away showing the means for transmitting the side swipe movement of the feeler through a flexible mem-

ber to the means for initiating filling replenishment.

Since the feeler has to feel into the shuttle on each detecting beat to ascertain the condition of filling therein, the detecting shuttle box and the front wall of the shuttle may conveniently be provided with a slot or opening for the entrance of the feeler. In the present instance of the invention, the shuttle 10 box 1 (Fig. 1) has its front wall 2 provided with an opening 3, and the shuttle 4 is likewise provided with a similar opening 5 adapted to register with the opening 3 of the front wall of the shuttle box for the entrance of the feeler when the shuttle is properly boxed. The shuttle 4 carries the bobbin or filling carrier 6 which may be held in the shuttle by any convenient means, which in the present instance of the invention is shown as the bobbin holding jaws 7 which are adapted to engage the rings 8 or the base or head portion of the bobbin 6.

Mounted in suitable bearings 9 secured to the loom frame 10 is the transverse or change 25 shaft 11 from which rises the arm 12 which is secured to rock with said shaft. Pivotaly mounted at 13 to the upper portion of the arm 12 is the arm 14, which for identification may be herein termed the actuator, be- 30 cause by its frontward movement, as will hereinafter more fully appear, replenishment of filling is initiated or effected. In order that the arm or actuator 14 may be properly guided or supported as it is moved 35 toward and from the front of the loom for rocking the transverse or change shaft 11, as will more fully appear, the said arm or actuator 14 has a foot portion 15 which may ride upon the upper surface of a part of the 40 loom frame 10. The construction described is found to be a convenient form of means for the parts noted, but it is to be understood that the invention is not restricted to these details, and may be variously devised with 45 respect thereto.

Pivotaly mounted at 16 on the rear end portion of the actuator 14 is the latch 17, the front portion 18 of which is adapted, under conditions to be presently described, 50 to engage the upper end portion 19 of an operating member 20 actuated from some moving part of the loom. In the present instance of the invention, the operating member 20 may be secured to or formed as 55 part of the cam follower or weft hammer.

As more clearly indicated in Fig. 6, the latch 17 has its end 18 normally lifted out of the path of the end 19 of the operating member by means of a spring 21 which may 60 be conveniently seated in a recess 22 formed in the actuator 14 or a part secured thereto. In order that the latch 17 may be properly restricted in its movements under the actuation of the spring 21, the actuator 14 is pro- 65 vided at its front end portion with a stop

23 (Fig. 6), the construction being such that the latch 17 will normally be held by the spring 21 in its dotted line position (Fig. 6) with the end 18 thereof out of the path of movement of the end 19 of the operating 70 member, but be adapted to have its end 18 depressed into the full line position (Fig. 6) to engage the operating member 20, as will more fully appear.

The feeler has to be supported in position to feel for the filling in the shuttle on each detecting beat, and to this end may be appropriately supported by any suitable means. In the present instance of the invention, a bracket 24 provided with a slot 25 is adapted to be adjustably secured to a part of the loom frame or other support by an adjusting bolt 26, and said bracket is formed on its top portion with a seat 27 for the appropriate support of a feeler stand. 80 The feeler stand may be variously devised, but as shown in the present instance of the invention, it comprises a plate 28 (Fig. 2) provided at its front portion with a loose bearing 29 and at its rear portion (Fig. 2) with a slot 30, said bearing and slot affording appropriate support for a feeler 31 which is adapted for movement toward and from the front of the loom and in a direction longitudinal of the shuttle in said bearings. The bearing 29 and slot 30 may be appropriately formed in lugs or upwardly projecting portions from the feeler stand plate 28 as indicated in Fig. 2. The feeler 31 is provided with a lug or projection 32 between which and the front portion of the feeler stand is interposed a spring 33 normally acting to hold the feeler 31 in its rearward or feeling position, as indicated in Fig. 2, with the lug 32 in engagement with the lug 34 rising from the feeler stand, the construction being such, that the spring 33 will normally hold the feeler in its rearward position, but will yield to permit the feeler to move frontwardly. The lug 32 of the feeler 100 has an inclined portion 35 which is adapted at times to engage a correspondingly inclined or cam portion 36 formed on the feeler stand, the construction being such, that should the feeler 31 be moved frontwardly 105 from the position indicated in Fig. 2, and then have imparted to it its side swipe movement longitudinally of the shuttle, as the lay beats up, the said inclines 35 and 36 will cause the feeler to move laterally in an opposite direction to its side swipe movement as the spring 33 forces the feeler into its rearward position.

In the present invention, means are provided for acting upon the feeler on each detecting beat tending to impart a side swipe movement to the feeler, and the end portion of the feeler is provided with a roughened or toothed surface, which by engagement with a working supply of filling will pre- 125 130

vent side swipe movement of the feeler in response to its actuating means until the filling has become substantially exhausted. In the illustrated form of the invention, the 5 means for imparting the side swipe movement to the feeler consists of a pivoted arm 37 mounted to rock about a fixed pin 38 rising from the feeler stand. The pivoted member 37 is placed under the control of 10 a spring normally acting to force the pivoted member 37 toward and against the feeler. In the present instance of the invention, on the pin 38 is mounted the collar 39 which is surrounded by a coil spring 40, 15 one end 41 of which is engaged with a hole or recess 42 (Fig. 2) in the pivoted member 37 and the other end 43 of which is engaged with a hole or opening 44 formed in the top portion of an inclosing sleeve or 20 collar 45. The inclosing sleeve or collar 45 is provided with a transverse opening 46 adapted to register with a corresponding opening 47 in the pin 38, and the cotter pin 49 is adapted to pass through the openings 25 46 and 47 to maintain the sleeve or collar 45 in adjusted position with the spring 40 under suitable tension. The pivoted member 37 extends from its pivotal support rearwardly and the side thereof adjacent the 30 feeler 31 is adapted to bear upon the lug 32, so that as the feeler 31 is moved frontwardly on a detecting beat, the pivoted member 37 may cause side swipe movement of the feeler provided it is free for said 35 movement.

It is expedient to relieve the feeler 31 from the pressure of the member 37 as the lay goes back after a detecting beat, in order to insure proper return of the feeler to 40 feeling position, should it have been given its side swipe movement. Various means may suggest themselves for this purpose, but in the present instance of the invention, the member 37 has joined to its rearward end 45 as at 50, a connection 51 to a relieving device. This device, in the illustrated form of the invention, consists of a sleeve 52 mounted to rock upon a supporting pin 53 (Fig. 1). The pin 53 may be suitably supported as by means of a bracket 54 secured to the loom frame. Extending from the sleeve 52 is an arm 55 to which the connection 51 is joined. The sleeve 51 has another arm 56 extending therefrom with its end 57 in the path of movement of the operating member 20, the construction being such, that when the lay has about completed its frontward movement on a detecting beat, the operating member 20 will engage the 50 end 57 of the arm 56 and cause the pivoted member 37 to relieve the feeler 31 of pressure, and permit it to move rearwardly into its feeling position.

A feature of the present invention consists in a locking member mounted inde-

pendently of the feeler to prevent side swipe movement of the feeler until the filling in the shuttle has reached a predetermined degree of exhaustion, and then to relieve the feeler from its locking relation therewith, in order that thereafter the feeler may indicate substantial exhaustion when the critical point is reached to effect filling replenishment. The locking member may be variously contrived, but in the present instance of the invention, it comprises the bar or rod 58 (Fig. 1) conveniently mounted for reciprocating movement in the feeler stand. This feature of the invention is embodied in the present instance in a cover plate 59 80 for the feeler stand, from which rises the front and rear bearing portions 60 and 61 in which the locking member 58 is mounted for reciprocating movement. A stop pin 62 limits the rearward movement of the 85 locking member 58 under the impulse of its spring 63, and cap pieces 64 secured to the top portion of the cover 61 maintain the locking member 58 and cover in position relative to the feeler stand by suitable securing means such as the screws 65. The feeler stand and cover may be properly secured together and be provided also with an adjusting slot 66, which by means of screws 67, permit the feeler to be adjusted 90 to desired position.

The feeler 31 has a filling engaging end portion adapted to engage the filling on a detecting beat and by sinking into the filling, prevent side swipe movement of the 100 feeler responsive to the member 37 until the filling has become substantially exhausted. In the present instance, the feeler 31 is provided with a series of teeth 68 (Fig. 2), and the feeling end of the feeler is 105 preferably provided with a recessed portion 69 into which projects a part of the locking member 58. In the present instance, the end of the locking member 58 is downturned as at 70 (Fig. 3), and the downturned end thereof rides in the recessed portion 69 of the feeler. The locking member may be provided with an adjustable portion 71, preferably formed as a screw bolt which may be secured in an adjustable position by a lock nut 72, the construction being such that so long as a working supply of filling remains in the shuttle, the end 110 of the locking member will remain in engagement with the recessed portion 69 of the 115 feeler and perforce lock the feeler from side swipe movement. When, however, the filling becomes so far exhausted that the locking member meets the wall of the shuttle or other part carried by the lay on a 120 detecting beat, before the end of the feeler engages the filling in the shuttle, the locking member will be moved frontwardly independently and prior to frontward movement of the feeler, thereby freeing the 125 130

feeler to its side swipe movement. After the feeler has thus been unlocked, the end 68 of the feeler will engage the filling on each succeeding detecting beat, and so long 5 as a working supply still remains in the shuttle, it will hold the feeler from side swipe movement responsive to the member 37, but when the filling has become substantially exhausted, it will no longer be able 10 to hold the feeler from side swipe movement responsive to the member 37, and thereupon the feeler will be moved in a direction longitudinal of the shuttle to initiate filling replenishment. 15 As hereinbefore pointed out, the latch 17 is normally maintained with its end 18 out of the path of movement of the operating member 20, but when the filling has become substantially exhausted and the feeler par- 20 takes of its side swipe movement, it is desir- 25 irable that the latch 17 be guided or moved into position for engagement with the operating member. In some aspects of the invention, various means may be contrived to this end, but in the present instance, a flexible member is interposed between the latch and the feeler and adapted to be moved lengthwise by the side swipe movement of the feeler to position the latch operatively 30 with respect to the operating member.

Pivottally mounted at 73 on a bracket 74 (Fig. 6) extending from the rear portion of the feeler stand, is the arm 75, the upper end 76 of which is in the path of side swipe 35 movement of the feeler 31, the construction being such, that so long as the feeler 31 partakes only of its movement toward and from the front of the loom on a detecting beat, the arm 75 remains quiet, but should the feeler 40 be moved in a direction longitudinal of the shuttle, that is, partake of its side swipe movement on a detecting beat as it moves frontwardly, the side of the feeler 31 while moving along the top portion 76 of the arm 45 75 will push said arm to one side as indicated in Fig. 6 and perforce rock it upon its pivot 73. This movement of the arm 75 is utilized to operate the latch 17, as will now be explained. Connected to the arm 75 is 50 an arm or lug 77 (Fig. 6) which normally rests upon a pin 78 which forms the end portion of a flexible member 79 extending from a point adjacent the feeler to a point adjacent the latch 17 as indicated in Fig. 6. In 55 the present instance of the invention, the flexible member 79 is formed of a wire inclosed in a casing 80 of such diameter as to prevent buckling of the wire when the pin 78 pushes the wire lengthwise. The end of 60 the wire 79 beneath the latch 17 is connected to a terminal 81 positioned at one side of the pivot 16 of the latch, and the latch is provided with an extended shelf or contact member 82, the construction being such, that 65 when the arm 76 is moved by the side swipe

movement of the feeler, the flexible member 79 will be pushed lengthwise against the part 70 82 of the latch and cause the end 18 of the latch to move into the path of the end 19 of the operating member. As the operating member moves frontwardly after detection by the feeler of substantial exhaustion, it will move the latch and perforce the actuator frontwardly, thereby rocking the change shaft 11 and initiating filling replenishment. 75

The terminal portion of the flexible member 79 may be appropriately secured in desired position by a small bracket or other supporting member 83 secured by a bolt 84 to a fixed part of the loom below the latch. 80

When the end 18 of the latch has been engaged by the operating member 20, and filling replenishment initiated, it is desirable, as the operating member moves backwardly away from the end of the latch, that the latch shall unmerringly move into inoperative position, that is, that the end 18 thereof be lifted by the spring 21, so that on the next detecting beat, when a full bobbin has been placed in the shuttle, there may not be another replenishing operation. To this end the part or extension 82 of the latch at its front portion is adapted to be engaged by the downturned end 85 (Fig. 1) of a resetting arm 86 secured to the operating member 90 20 as by means of the pins 87, the construction being such, that after a replenishment of filling, and as the operating member 20 returns to its backward position, the resetting arm 86 will act upon the latch to insure 100 the end 18 thereof being moved out of operative relation with the operating member, so that on the next operating movement of the shuttle, unnecessary replenishment of filling may not be effected. 105

From the construction described, as one good form of the present invention, and from the characteristic relation of the feeler and locking members, it will be noted that the feeler will be locked from side swipe movement responsive to its actuating means until the filling has been depleted to a point approaching substantial exhaustion, and then will be unlocked, so that thereafter side swipe movement of the feeler will be prevented until the filling has been substantially exhausted by engagement with the engaging end of the feeler with the filling. Should the shuttle fail to be properly boxed, the filling engaging end of the feeler will strike the smooth wall of the shuttle, and in the absence of means to prevent, it would, under the principle of the side swipe feeler construction, move longitudinally of the shuttle, and effect filling replenishment at 110 an undesirable time. The locking member, however, will continue in locking engagement with the feeler when the shuttle is not properly boxed on a detecting beat, and replenishment will not be effected. 115 120 125 130

Claims:

1. In a feeler motion for looms, the combination of a feeler having a filling engaging portion to engage and be held by the filling from movement longitudinally of the shuttle on a detecting beat until substantial exhaustion of filling occurs, means tending to move the feeler longitudinally of the shuttle on each detecting beat of the lay, and a locking member for normally preventing feeler movement longitudinally of the shuttle until the filling has reached a predetermined degree of exhaustion and then being moved frontwardly independent of the feeler movement by engagement with the shuttle wall and freeing the feeler that the feeler may respond to the means tending to move it longitudinally of the shuttle when the filling becomes substantially exhausted.
2. A feeler motion for looms, comprising, in combination, a feeler member mounted for movement longitudinally of the shuttle and moved frontwardly on each detecting beat by the forward pressure upon it, means acting upon the feeler on a detecting beat tending to move the feeler in a direction longitudinally of the shuttle, a lock unrestraining the feeler member to full rearward movement and acting to prevent movement longitudinally of the shuttle until the filling has reached a predetermined degree of exhaustion and then being actuated by the shuttle for freeing the feeler to such movement, and a filling engaging end on the feeler to prevent movement of the feeler longitudinally of the shuttle by engagement with the filling until substantial exhaustion of filling.
3. A feeler motion for looms, comprising, in combination, a feeler member having a filling engaging end portion to engage the filling on each detecting beat and be held by the filling from movement longitudinally of the shuttle on a detecting beat until substantial exhaustion of filling, means tending to move the feeler member longitudinally of the shuttle, and a locking member movable toward the front of the loom independently of the feeler member and having a part engaging the feeler member to prevent movement of the feeler member longitudinally of the shuttle until the filling has reached a predetermined degree of exhaustion, and then disengaging the feeler member that the feeler member may respond to the means tending to move it longitudinally of the shuttle when the filling reaches a condition of substantial exhaustion.
4. A feeler motion for looms, comprising, in combination, a feeler mounted in front of and independently of the lay to enter the shuttle on each detecting beat and be moved frontwardly by the push upon it, means acting upon the feeler on a detecting beat tending to give the feeler a side swipe movement longitudinally of the shuttle, a lock that permits movement of the feeler to full feeler position and acting to prevent side swipe movement of the feeler responsive to said means until the filling has been exhausted to a predetermined degree and then moved frontwardly by engagement with the shuttle to disengage the feeler, an end portion carried by the feeler to prevent side swipe movement of the feeler by engagement with the filling after it is unlocked and until substantial exhaustion of filling, and means for changing the operative condition of the loom when substantial exhaustion of filling permits side swipe movement of the feeler.
5. A feeler motion for looms, comprising, in combination, a feeler mounted in front of and independently of the lay to enter the shuttle on each detecting beat and be moved frontwardly by the push upon it, means acting upon the feeler on a detecting beat tending to give the feeler a side swipe movement longitudinally of the shuttle, a lock mounted for movement toward and from the front of the loom independently of the feeler by engagement with the shuttle on each detecting beat for preventing the side swipe movement of the feeler responsive to said means until the filling has been exhausted to a predetermined degree, an end portion carried by the feeler to prevent side swipe movement of the feeler by engagement with the filling after it is unlocked and until substantial exhaustion of filling, and means for changing the operative condition of the loom when substantial exhaustion of filling permits side swipe movement of the feeler.
6. A feeler motion for looms, comprising, in combination, a feeler having an end portion to engage the filling and hold the feeler from movement longitudinally of the shuttle until the filling is substantially exhausted on a detecting beat, a movable member having a part extending into the path of the feeler as it moves longitudinally of the shuttle when the filling is substantially exhausted, a flexible member movable lengthwise by the movable member when said movable member is actuated by movement of the feeler longitudinally of the shuttle, and means controlled by the flexible member for effecting replenishment of filling.
7. In a feeler motion for looms, the combination of a feeler having a filling engaging portion to engage and be held by the filling from side swipe movement longitudinally of the shuttle on a detecting beat until substantial exhaustion of filling, a lock for preventing side swipe movement of the feeler until the filling has reached a predetermined degree of exhaustion and then actuated by engagement with the wall of the shuttle to unlock the feeler, a flexible member adapted to be moved lengthwise by the side swipe movement of the feeler, and means controlled by

the flexible member for changing the operative condition of the loom when the flexible member is moved lengthwise by the side swipe movement of the feeler.

- 5 8. A feeler motion for looms, comprising, in combination, a feeler, means acting upon the feeler and tending to move it longitudinally of the shuttle, a lock to prevent movement of the feeler longitudinally of the shuttle until the feeler enters the shuttle to a predetermined extent and then freeing it to the action of said means by engagement with the wall of the shuttle, an end portion on the feeler to prevent its movement longitudinally of the shuttle when unlocked by engagement with the filling on a detecting beat until substantial exhaustion of filling, a flexible member adapted to be moved lengthwise by movement of the feeler longitudinally of the shuttle, and means controlled by the flexible member for initiating replenishment of filling when the flexible member is moved lengthwise by the side swipe movement of the feeler.
- 15 9. A feeler motion for looms, comprising, in combination, a feeler having a portion to engage the filling and hold the feeler from side swipe movement longitudinally of the shuttle until the filling is substantially exhausted on a detecting beat and then permitting such side swipe movement, a movable member actuated by the side swipe movement of the feeler, a flexible member movable lengthwise by the movable member when said movable member is actuated by the side swipe movement of the feeler, and means controlled by the flexible member for initiating filling replenishment.
- 20 10. A feeler motion for looms, comprising, in combination, a feeler having a portion to engage the filling and hold the feeler from side swipe movement longitudinally of the shuttle until the filling is substantially exhausted, means adapted to act upon the feeler and tending to impart a side swipe movement thereto on a detecting beat, a lever having a part projecting into the path of side swipe movement of the feeler, a flexible push member adapted to be moved lengthwise by the lever, and means controlled by the flexible member for initiating filling replenishment.
- 25 11. In a feeler motion for looms, the combination of a feeler mounted for side swipe movement and moved toward the front of the loom on each detecting beat, a lock mounted for longitudinal movement independently of the feeler and acting to prevent side swipe movement of the feeler until the filling has reached a predetermined degree of exhaustion and then freeing the feeler to its side swipe movement, means tending to impart side swipe movement to the feeler, and an end portion on the feeler to engage
- 30 the filling in the shuttle and hold the feeler

from side swipe movement until substantial exhaustion of filling.

12. In a feeler motion for looms, the combination of a feeler mounted for movements toward and from the front of the looms and longitudinally of the shuttle, a spring actuated member tending to move the feeler longitudinally of the shuttle and along which the feeler travels as it moves toward and from the front of the loom, an operating member, connections between the spring actuated member and operating member to relieve the feeler from the action of the spring actuated member when the lay reaches front position on a detecting beat, and an end on the feeler to engage the filling and prevent movement of the feeler longitudinally of the shuttle until the filling is substantially exhausted.

13. In a feeler motion for looms, the combination of a feeler that is moved toward the front of the loom on each detecting beat by the frontward pressure upon it and having a filling engaging portion to engage the filling and hold the feeler from side swipe movement until the filling is substantially exhausted, means acting upon the feeler on a detecting beat tending to impart a side swipe movement, a locking member mounted for movement independently of the feeler on a detecting beat and serving by relative movement of the feeler and locking member when the feeler contacts with an improperly boxed shuttle to continue its locking function and prevent side swipe movement of the feeler.

14. In a feeler motion for looms, the combination of a feeler that is moved toward the front of the loom on each detecting beat and having an end to prevent movement longitudinally of the shuttle by engagement with the filling and permit such movement when the end of the feeler engages the body of an improperly boxed shuttle, a locking member mounted independently of the feeler for movement toward and from the front of the loom and having a part extending into the path of the feeler as it moves longitudinally of the shuttle, and means for maintaining the locking member in feeler locking position when the feeler and locking member are relatively moved by an improperly boxed shuttle.

15. In a feeler motion for looms, the combination of a side swipe feeler to feel for and engage a surface within the shuttle on each detecting beat and be moved toward the front of the loom, a locking bar mounted for movement toward and from the front of the loom independently of the feeler and having a feeler locking portion to engage and lock the feeler from movement longitudinally of the shuttle until the locking bar is moved frontwardly in advance of the frontward movement of the feeler, means

tending to move the feeler longitudinally of the shuttle, an end on the feeler to prevent longitudinal movement of the feeler by engagement with the filling after the feeler is unlocked until substantial exhaustion of the filling.

16. In a feeler motion for looms, the combination of a feeler member supported independently of the lay and moved frontwardly on each detecting beat by the pressure upon it, means tending to move the feeler member in a direction longitudinally of the shuttle, a locking member having a projection extending into the path of movement of the feeler member to prevent side swipe action thereof until the filling reaches a predetermined degree of exhaustion and thereupon moved by engagement with the shuttle to carry the projection out of the path of feeler movement to permit such side swipe action, and means for effecting filling replenishment when the feeler is moved longitudinally of the shuttle.

17. In a feeler motion for looms, the combination of a feeler member supported independently of the lay and moved frontwardly on each detecting beat by the pressure upon it, means tending to move the feeler member in a direction longitudinally of the shuttle, a locking member moved toward the front of the loom on each detecting beat and having a toe or finger extending alongside a part of the feeler member to prevent movement thereof longitudinally of the shuttle until the filling is exhausted to a predetermined degree and then being moved to carry the toe or finger out of obstructing position, and means for effecting replenishment of filling when the feeler member is moved longitudinally of the shuttle.

18. A feeler motion, comprising, in combination, a feeler member mounted independent of the lay to feel for the filling and be moved frontwardly on each detecting beat, means tending to give the feeler member a side swipe movement, a shoulder carried by the feeler member, a locking member having a projection extending into the side swipe path of movement of the feeler member to obstruct such movement until the filling reaches a predetermined degree of exhaustion and then being moved out of obstructing position, and an end on the feeler member to thereafter prevent side swipe movement of the feeler member until substantial exhaustion of filling.

19. A feeler motion, comprising, in combination, a feeler member mounted independent of the lay to feel for the filling and be moved frontwardly on each detecting beat, means tending to give the feeler member a side swipe movement, a recessed portion on

the feeler member extending toward but terminating short of the end of the feeler member, a locking member having a projection extending into said recessed portion on the feeler member to prevent movement of the feeler member longitudinally of the shuttle while in engagement therewith and adapted to engage the terminal portion of the recess and be moved by it when the feeler is struck by an improperly positioned shuttle.

20. A feeler motion, comprising, in combination, a feeler stand, a feeler member mounted on the stand and moved frontwardly by the push upon it, a spring actuated arm adapted to bear upon the feeler member to move it in a direction longitudinally of the shuttle when the filling is substantially exhausted, a locking member having a toe or finger engaging a side portion of the feeler member, a spring normally acting to hold the locking member in rear position but permitting the locking member to be moved frontwardly coincident with the feeler member to maintain the toe or finger at the side portion of the feeler member until the filling is exhausted to a predetermined extent and then causing the locking member to be moved frontwardly an increased amount relative to the feeler member to carry the toe or finger out of obstructing relation with the feeler member.

21. A feeler motion, comprising, in combination, a feeler member moved frontwardly on each detecting beat by the push upon it, an arm along which the feeler moves as it travels frontwardly, a spring acting on said arm and tending to move the feeler member in a direction longitudinally of the shuttle, a rock shaft connected to the said arm, an arm extending from the rock shaft and an operating member adapted to engage said arm as said member moves frontwardly, rock said shaft, and relieve the pressure of the spring actuated arm from the feeler member.

22. In a feeler motion for looms, the combination of a feeler member having a filling engaging end adapted to hold the feeler member from side swipe movement longitudinally of the shuttle until substantial exhaustion of filling, an actuator carrying a latch, an operating member for engaging the latch when it is moved into operative relation thereto by side swipe movement of the feeler member, and a resetting device for the latch connected to the operating member and acting to reset the latch as the operating member moves back.

In testimony whereof, I have signed my name to this specification.

ALONZO E. RHOADES.
